Edgar Dale & Co.

UNITED STATES PATENT OFFICE.

FRANKLIN C. FUELLING, OF ROSLYN, NEW YORK.

IRONING-BOARD.

1,337,512.

Specification of Letters Patent. Patented Apr. 20, 1920.

Application filed June 26, 1919. Serial No. 306,812.

To all whom it may concern:

Be it known that I, FRANKLIN C. FUELLING, a citizen of the United States, and residing at Roslyn, L. I., in the county of 5 Nassau and State of New York, have invented certain new and useful Improvements in Ironing-Boards, of which the following is a specification, such as will enable those skilled in the art to which it appertains to 10 make and use the same.

This invention relates to ironing boards and the object thereof is to provide a device of this class which is combined with an ordinary table designed for general use, and 15 which forms a part of the table and is normally flush therewith but which may be raised and supported above the table when necessary for use as an ironing board.

The invention is fully disclosed in the following specification, of which the accompanying drawing forms a part, in which the separate parts of my improvement are designated by suitable reference characters in each of the views, and in which:—

25 Figure 1 is a longitudinal sectional view of a table provided with my improved ironing board and indicating the method of its use;

Fig. 2 is a sectional and bottom plan view 30 of a table; and,

Fig. 3 a section on the line 3—3 of Fig. 1. In the drawing forming part of this specification I have shown at a a table comprising a main box member a^2 consisting of sides a^3 and ends a^4 , and the box member a^2 is provided with legs a^5 , and placed on said box member is the usual table or table board a^6 in one side portion of which is a longitudinal aperture or opening a^7 adapted to receive an ironing board b of the usual or any preferred form, and the shape of which conforms to the shape of the board as indicated in Figs. 2 and 3. Within and arranged longitudinally of the main box member a^2 is a longitudinal chamber a^8 formed by a longitudinal partition wall a^9 , and at one end of the chamber a^8 is a transverse support a^{10} , and secured in and to the bottom of the chamber a^8 or to the bottom of the part a^9 , and one 45 of the parts a^3 , is a transverse angle-iron support or keeper c , which is V-shaped in cross section.

The bottom of the table b is also provided adjacent to the larger end thereof, in the 55 construction shown, with a hanger b^2 , and adjacent to the opposite end with a block b^3

having an inwardly directed tongue or keeper b^4 .

I also provide a toggle lever device d consisting of two parts d^2 and d^3 , which are 60 pivotally connected at d^4 , and each of which consists of parallel side members. One end of the toggle lever member d^2 is pivoted to the hanger b^2 at e and is beveled as shown at d^5 , while the other end of the toggle lever 65 member d^2 is pivoted in one end of the chamber a^8 as shown at e^2 .

The toggle lever member d^3 is provided at one end with a V-shaped head d^6 adapted to fit in the V-shaped support c , and at the 70 other end with a transverse head piece d^7 having a V-shaped recess d^8 adapted to receive the tongue b^4 of the block b^3 .

In the normal position of these parts the ironing board b is in the position shown in 75 full lines in Fig. 1 and the table a may be used for any desired purpose, but when it is desired to use the ironing board pressure is applied to the bottom of said board from beneath, and said board is raised into the 80 position shown in dotted lines in Fig. 1, in which position the ends of the toggle lever member d^3 engage the parts c and b^3 as clearly indicated in dotted lines, and the ironing board is firmly held in its raised 85 position and may be used in the same manner as other devices of its class, and when the use of said board is finished, it may be lowered into the position shown in full lines in Fig. 1 by slightly raising it and allowing the toggle lever member d^3 to swing freely.

With my improvement, as will be seen, I provide a combined table and ironing board which may be used for either of the purposes named, whenever necessary, and a saving of space is thus effected together with a saving in the manufacture of articles of the class referred to, and while I have shown and described certain forms of construction 95 necessary in carrying my invention into effect, the invention is not limited to the details of construction herein shown and described, and changes therein and modifications thereof may be made, within the scope 100 of the appended claims, without departing from the spirit of the invention or sacrificing its advantages.

It will be seen on consideration of Figs. 1 and 2 of the drawing that when the ironing board b is in its normal position it rests 110 on the transverse support a^{10} , one of the

2
sides a^3 of the box member a^2 and the longitudinal partition wall a^9 . It will also be seen that by reason of the tongue and groove connection of the toggle lever members d^3 with the block b^3 , the ironing board b , or the free end thereof, is held against lateral movement on said lever members, and by reason of the V-shaped form of the support c and the V-shaped head d^6 on the lever members d^3 , the ironing board b is against upward tilting when downward pressure is applied to the block end b^3 of the board.

Having fully described my invention, what I claim as new and desire to secure 15 by Letters Patent, is:—

A table provided with an aperture of the shape of an ironing board, an ironing board adapted to fit in said aperture, said ironing board being provided on the bottom of one 20 end portion thereof with a keeper and the

frame of the table being provided with another keeper, a toggle lever member pivoted to the bottom of one end portion of the board opposite the first named keeper, and another toggle lever member pivoted centrally of the first named toggle lever member and the ends of which are adapted to engage and operate in connection with said keepers whereby the board may be raised and lowered in an elevated position for use 25 and lowered when not in use into said aperture flush with the table.

In testimony that I claim the foregoing as my invention I have signed my name in presence of the subscribing witnesses this 25th day of June 1919.

FRANKLIN C. FUELLING.
